(57) **CLAIM**

The ornamental design for an LED grow light, as shown and described.

DESCRIPTION

FIG. 1 is a front, right and bottom perspective view of an LED grow light, showing my new design;

FIG. 2 is a rear, left and top perspective view thereof;

FIG. 3 is a front view thereof;

FIG. 4 is a rear view thereof;

FIG. 5 is a left side view thereof;

FIG. 6 is a right side view thereof;

FIG. 7 is top plan view thereof;

FIG. 8 is bottom plan view thereof;

FIG. 9 is an enlarged view of portion of FIG. 1 thereof;

FIG. 10 is an enlarged view of portion of FIG. 1 thereof; and, FIG. 11 is an enlarged view of portion of FIG. 2 thereof.

The dash-dash broken lines shown in the drawings illustrate portions of the LED grow light that form no part of the claimed design. The dash-dot broken line circles in FIGS. 1-2 and 9-11 define the bounds of the enlargements and do not form part of the claimed design.

1 Claim, 11 Drawing Sheets
